UNITED STATES PATENT OFFICE.

WILLIAM H. LUDEWIG, OF ROCK ISLAND, ILLINOIS.

FLUSHING-VALVE-OPERATING DEVICE.

No. 853,813.

Specification of Letters Patent.

Patented May 14, 1907.

Application filed December 20, 1906. Serial No. 348,794.

To all whom it may concern.

Be it known that I, WILLIAM H. LUDEWIG, of Rock Island, in the county of Rock Island and State of Illinois, have invented certain new and useful Improvements in Flushing-Valve-Operating Devices; and I hereby declare that the following is a full, clear, and exact description thereof, reference being had to the accompanying drawings, which form part of this specification.

This invention is an improvement in water-closets, and particularly relates to the flushing valve operating device for water-closets and the like, and in the connections between the closet bowl and the tank. Its objects are to produce a construction wherein the flushing-tank can be located and supported if desired directly upon the bowl; and to provide automatically operating seat controlled mechanism for opening the flushing-valve when the seat is released, said devices being set by pressure upon the seat and operated automatically by a spring when the seat is released.

Further objects are to make the parts strong, compact and durable, and to render the operative parts easily detachable and replaceable in case repairs are necessary.

The invention will be clearly understood from the following description and the accompanying drawings forming part of this application, and the features and parts and combinations of parts for which protection is desired are set forth in the claims following the specification.

In the drawings—Figure 1 shows a front view of the tank partly broken away, and sectional view of bowl with seat removed. Fig. 2 is an enlarged vertical sectional view through the flushing-valve on line 2—2, Fig. 3. Fig. 3 is a sectional view on line 3—3, Fig. 1. Fig. 4 is a part plan view and part horizontal sectional view of the bowl and parts therein. Fig. 5 is a detail section showing the flush-valve operating devices in position assumed after flush-valve is opened, and just before the catch disengages the dog. Figs. 6, 6^a and 7 are detail perspective views of the valve-operating lever and its fastening devices. Fig. 8 is a perspective view of the lever engaging roller and its supporting casting. Figs. 9 and 9^a are detail perspective views of the valve operating dog and catch. Fig. 10 is a perspective view of the housing for the valve operating devices.

The closet bowl 1 is preferably oval in

form, and has a rearward extension 1^a adapted to support the flushing-tank T, as hereinafter explained. In this extension 1^a is formed a cavity 1^b, adapted to contain a metal casing 2, hereinafter referred to, and from the cavity 1^b extend inwardly three ducts, a central horizontal passage 1^c, and two horizontal side passages or ducts 1^d, 1^d, the latter being adapted to conduct water from the flush-tank to the bowl, as hereinafter explained, and may connect with the usual distributing passages, not shown, in and around the upper edge of the bowl. The passage 1^c is occupied by a tube 2^a, connected with the metal casing 2 for a purpose hereinafter explained.

The casing 2 may be rectangular or of other desired form, large enough to contain the flush-valve operating devices, and is preferably provided at bottom with side flanges 2^b adapted to engage recesses in the sides of cavity 1^b, so as to anchor the casing firmly in cavity 1^b, and the casing is provided at top with a horizontal flange 2^c which is adapted to rest upon the top of extension 1^a. After the casing is in place it may be sealed in the cavity by filling up the open end of the latter with cement, as indicated at 1^e or in other suitable manner.

The tube 2^a extends from the forward side of the casing through the passage 1^c, and may be sealed therein by any suitable cement or packing; while the front wall of the casing has openings 2^d, which communicate with the inner ends of the water ducts 1^d, 1^d, as shown.

On the top of the casing and projecting above the same sufficiently to enter the bottom of the flushing-tank T, is a circular flange 2^e which fits tightly in an opening in the bottom t of the flushing tank which is set over the casing 2 and upon the extension 1^a of the bowl as shown.

Telescoped into the circular flange 2^e is a cylinder 3, having a flared seat 3^a on its upper end for the accommodation of the flush-valve V, and this cylinder is provided with an external flange 3^c adapted to rest upon the top surface of the bottom t of the tank. When the cylinder is fastened to the casing, water-tight joints can be formed between the bottom of the tank and the flange 2^e on the casing and flange 3^c on the cylinder 3, suitable washers 2^x, 3^x being interposed between said flanges and the bottom of the tank as indicated in the drawings. The cylinder 3 may be detachably secured to the

casing 2 in any desired manner; I now prefer to form the cylinder with upper and lower transverse bridge pieces 3^d, 3^e, connected by a central tube 3^f, and through these bridge pieces are passed bolts 3^g which screw into lugs 2^g on the inside of the casing as shown, and thus firmly secure the cylinder 3 and flushing-valve seat 3^a to the casing, and also fasten the tank onto the bowl.

10 The tube 3^f forms a guide for the stem *v* of the flushing-valve *V* which is guided in its rising and falling movements by said stem. When the valve is closed the stem *v* depends into the casing (as indicated in Figs. 2 and 3), 15 and when it enters the casing it contacts with a dog 4 pivoted in the casing, or rather on the lower end of cylinder 3, see Figs. 3 and 5. This dog carries a roller 4^a in position to engage the lower end of the valve-rod *v*, and 20 form a rolling contact between the stem and dog. The dog has a normally depending tooth 4^b which when the dog is raised, stands opposite the inner end of the tube 2^a; and at each side of the tooth 4^b are downwardly and 25 rearwardly curved fingers 4^c slightly longer than the tooth and for a purpose hereinafter explained. A spring 4^d is arranged to hold the dog upwardly when the valve *V* is raised. Within the casing below the dog is a catch 30 5 which is provided with a tooth 5^b adapted to engage tooth 4^b of the dog when the catch is pushed inward and the dog is in its lowermost position (Fig. 3). The catch is also provided at each side of its tooth 5^b with upwardly curved fingers 5^c adapted to co-act with fingers 4^c as hereinafter explained. The 35 catch 5 is pivoted at its forward end to the inner end of a rod 6 which lies in tube 2^a, and a spring 5^d is arranged to normally press the 40 catch upwardly into engaging position.

The inner end of rod 6 is enlarged as at 6^a to fit in the tube neatly and hold the rod axially in position in the tube, while the outer end of the rod is reduced in diameter as at 6^b 45 and is guided in the bore of a sleeve nut 2^m tapped into the inner end of tube 2^a, and provided with apertures 2ⁿ so that any water entering the tube can readily escape therefrom. By removing nut 2^m the rod 6 can be 50 easily inserted in and removed from the tube 2^a. The rod 6 moreover is provided intermediate its ends with a slot 6^c crossed by a pin 6^d carrying a roller 6^e which is engaged by the lower yoked end of a lever 7 which is 55 attached to the lower forward side of the tank, or tank bottom plate, and depends through a slot 1^o in the bowl extension and a slot 2^o in the upper side of tube 2^a, and engages rod 6, as described. Obviously by 60 swinging lever 7 the rod 6 will be reciprocated, and the catch 5 moved into or out of engagement with the dog 4. The rod 6 can be moved and held in outermost position by a spring 6^p interposed between the shoulder 2^r 65 at the inner end of tube 2^a, and a collar 6^r on

the rod in rear of lever 7. The forward movement of the rod and lever under the action of spring 6^p being regulable, if desired, by a nut 6^s threaded on part 6^b, and engaging the sleeve nut 2^m.

The lever 7 is pivoted at its upper end by a pin 7^a to a bracket casting 7^b, which in turn is detachably fastened in a casting 7^c attached to the front edge of the bottom plate *t* of the tank as shown. The casting 7^c has laterally extending portions 7^d which afford a means for securely attaching it by screws to the tank bottom plate; and it also has a central rearwardly extending portion 7^e which is fitted into a recess in the bottom 75 plate *t* and is provided on its rear end with a depending perforated lug 7^f through which passes a bolt 7^g the forward end of which has a head 7^h impinging against a roller 7ⁱ on the lever 7, and a stout helical spring 7^j is interposed between lug 7^f and the head 7^h of the bolt, and forcibly swings lever 7 outward, and normally holds said lever 7, and with it rod 6, in outermost position, as shown in full lines in Fig. 3. The extent of 80 outward movement of the lever can be regulated by an adjusting nut 7^k on the threaded rear end of bolt 7^g. In some cases one of the springs 7^j or 6^p could be omitted.

The closet seat *S* is hinged to the bottom 85 plate or support of the tank above lever 7 as shown in Figs. 1 and 3. The hinge lugs *s* are preferably made with unusually high pintles so as to cause the rear edge of the seat to swing more readily and farther than ordinary eye-hinges would do.

To the rear lower edge of the seat is attached a casting 8, (Figs. 3 and 8) carrying a roller 8^a which normally impinges against the forward side and upper part of lever 7 so 90 that when the seat is unoccupied it will be swung upward, as indicated in Fig. 8, by the action of spring 7^j, but when the seat is depressed the spring is tensioned and lever 7, rod 6 and catch 5 are moved back to the position indicated in dotted lines in Fig. 3.

The flush-valve *V* may be of any desired construction; as shown it has a head to fit the seat, and is provided with a tubular overflow member *V'*; and above the valve 95 proper is a flange *v'* which when the valve is raised is engaged by a dog 9 pivoted in the tank, and said dog upholds the valve until the water has escaped and the dog is released by mechanism operated by the descent of the 100 float *F*, controlling the inlet valve. This mechanism is not claimed herein and further explanation thereof is unnecessary, it is described and shown in my application Serial No. 319,534, filed May 31, 1906.

In addition to supporting the tank upon the extension 1^a by fastening it to the casing 2 as described, the tank may be additionally secured in position if desired by any ordinary means, not shown. In order to prevent its 105

rocking upon the casing and extension 1^a, I provide the extension with leveled studs 1^b, engaging sockets in the bottom plate *t* of the tank so that when the cylinder is secured in 5 position, as shown in Fig. 3, the tank will be securely held in place; ordinarily additional supports will be unnecessary.

Operation. Normally the flushing-valve *V* is closed, and the closet-seat raised, as 10 shown in full lines in Fig. 3. In this position the stem *v* engages roller 4^a and depresses dog 4 into the position shown in Fig. 3. When the seat *S* is depressed it will, through casting 8, force lever 7 rearward, tensioning 15 spring 7^j and moving rod 6 and catch 5 rearwardly;— catch 5 riding under dog 4 until tooth 5^b springs up behind tooth 4^b, as indicated in dotted lines in Fig. 3. Then when the seat is released spring 7^j throws the seat 20 up into the position shown in dotted lines Fig. 3, and pulls rod 6 and catch 5 forward, and as catch 5 is then engaged with dog 4 it swings the dog forwardly, as indicated in Fig. 5, causing roller 4^a to raise stem *v* and 25 thus unseat and raise valve *V*, which is upheld by dog 9, as indicated in dotted lines in Fig. 1 which shows the dog swung fully upward, and in the position assumed the moment before catch 5 has completed its outward stroke, at which moment fingers 4^c engage fingers 5^c and as the catch completes its stroke, the fingers cause the teeth to disengage and the dog is free to be swung back to the position shown in full lines Fig. 3, when 30 the valve *V* is released. The valve is released by the operation of the float-controlled mechanism as described in my aforesaid application; or by any other suitable connection with the inlet-valve controlling 35 mechanism, so that after the tank has emptied itself the flush-valve will be closed. The seat can be raised when closet is used as a urinal, and bowl subsequently flushed by momentarily depressing and then releasing 40 the seat.

Having described my invention what I claim as new and desire to secure by Letters Patent is:

1. In combination with a bowl, a flushing-50 tank, a flushing-valve in said tank having a depending stem, a dog below the tank adapted to be shifted by the stem when the valve is closed, a reciprocatory catch adapted to engage the dog, and means for reciprocating the catch to cause it to move the dog and open the valve.

2. In combination with a bowl, a flushing-55 tank supported thereon, a flushing valve in said tank having a depending stem, a swinging dog below the tank adapted to be depressed by the stem when the valve is closed, a catch adapted to engage the dog, means for reciprocating the catch, a spring for operating said means in one direction, and means 60 for moving it in opposition to the spring.

3. In combination, a flushing tank, a flushing valve, and a hinged seat with a swinging dog below the valve adapted to be moved by the closing of the valve, a reciprocatory catch adapted to engage the dog 70 and cause it to open the valve when the catch is moved in one direction, a spring for causing the valve-opening movement of the catch and means actuated by the seat for moving the catch in opposition to the spring. 75

4. The combination of a bowl, a hinged seat, a flushing tank, a flushing valve provided with a depending stem, a dog pivoted below the stem and adapted to be depressed thereby, a reciprocatory catch adapted to 80 engage the dog, a rod for operating said catch, a swinging lever engaging said rod, a spring for throwing said lever in one direction and devices connected with the seat for moving the lever in the opposite direction. 85

5. The combination with a flushing tank, a casing beneath the tank, a swinging dog in said casing, a catch slidably mounted in said casing and adapted to engage the dog, means actuated in one direction by a spring for reciprocating said catch, and a flushing valve having a depending stem adapted to engage and depress the dog when the valve is closed. 90

6. The combination of a flushing tank, a casing beneath the tank, a swinging dog in 95 said casing, a tube connected with said casing, a rod slidably mounted in said tube, a catch pivoted to the inner end of said rod adapted to engage the dog, means for reciprocating said rod, and a flushing valve having a depending stem adapted to engage and depress the dog when the valve is closed. 100

7. In combination with a valve having a stem, a pivoted dog adapted to engage the stem and provided with a tooth and curved 105 fingers; a catch having a tooth to engage the tooth of the dog and curved fingers adapted to engage the fingers of the dog, and means for reciprocating said catch.

8. In combination, a flushing tank and an 110 outlet valve having a depending stem, with a dog pivoted below the valve and having a roller adapted to engage the stem, and a tooth and curved fingers; with a catch having a tooth and curved fingers respectively 115 adapted to engage the tooth and fingers of the dog, and means for reciprocating said catch.

9. In combination with a flushing tank, an outlet valve having a depending stem, and a 120 pivoted dog adapted to be moved by the stem and having a tooth and curved fingers; with a catch having a tooth to engage the dog and curved fingers adapted to engage the 125 fingers of the dog, a reciprocatory rod engaging the catch, a swinging lever engaging said rod, a spring for moving the lever in one direction, and means for moving the lever in the opposite direction.

10. The combination of a flushing tank, an 130

outlet valve having a depending stem, a dog pivoted below the valve and adapted to engage the stem, with a catch adapted to engage the dog, a reciprocatory rod engaging the catch, a swinging lever engaging said rod, a spring for moving the lever in one direction, and a hinged seat and connections for moving the lever in the opposite direction.

11. In combination, a bowl having a rearward extension and a recess and forwardly extending passages in the upper end of said extension, a casing secured in said recess, a flushing tank mounted over said casing on said extension, an outlet in the tank communicating with the casing, a flushing valve for closing said outlet, means in the casing for opening the valve, and a hinged seat and connections for controlling said means.

12. In combination, a bowl having a rearward extension provided with a recess in its upper end, a casing secured in said recess, a flushing tank mounted over said casing on said extension, an outlet in the tank communicating with the casing, a valve for closing said outlet having a stem depending into the casing, a dog pivoted in the casing adapted to be depressed by said stem, a catch adapted to engage the dog, and means for reciprocating said catch.

13. The combination of a bowl having a rearward extension, a recess in the upper end of said extension, a casing secured in said recess, a flushing tank mounted over said casing on said extension, an outlet in the tank communicating with the casing, and a flushing valve for closing said outlet having a stem depending into the casing; with a dog pivoted in the casing adapted to be engaged by said stem, and means for moving said dog, a spring for operating said means in one direction, and a hinged seat and connections for operating said means in the opposite direction.

14. In combination, a bowl having a rearward extension, a recess in the upper end of said extension, a casing secured in said recess, a flushing tank mounted over said casing on said extension, an outlet in the tank communicating with the casing, a valve for closing said outlet having a stem depending into the casing, a dog pivoted in the casing adapted to be depressed by said stem, a catch adapted to engage the dog, a reciprocatory rod connected to said catch, a pivoted lever engaging said rod, a spring for moving the lever in one direction, and a hinged seat and connections for moving the lever in the opposite direction.

15. The combination of a bowl, a casing secured to the bowl, a flushing tank over the casing, a cylinder passing through the bottom of the tank and into the casing and provided with a flushing valve seat on its upper end, and means for fastening the cylinder to

the casing; with a flushing valve adapted to fit said seat, means in said casing for opening the flushing valve, a hinge seat and connections for setting the valve opening means, and a spring for actuating the valve opening means when the seat is released.

16. The combination of a bowl having a rearward extension, a casing secured in said extension, a flushing tank supported on the extension over the casing, a cylinder passing through the bottom of the tank and into the casing provided with a flushing valve seat on its upper end, means for fastening the cylinder to the casing, a flushing valve adapted to fit said seat and having a stem depending into the casing, means in said casing for opening the flushing valve, a hinge seat and connections for setting the valve opening means, and a spring for actuating the valve opening means when the seat is released.

17. The combination of a bowl having a rearward extension provided with a cavity in its upper portion, a casing secured in the cavity, a flushing tank secured over said casing, a cylinder passed through the bottom of the tank into the casing, and means for fastening the cylinder to the casing; with a flushing valve above the cylinder having a stem depending into the casing, a swinging dog pivoted in the casing adapted to be depressed by the stem when the valve closes, a reciprocatory catch in the casing adapted to engage the dog and cause it to open the valve when moved in one direction, a reciprocating rod connected to said catch, a spring for moving said rod in one direction, a hinged seat and connections for moving the rod in the opposite direction, when the seat is depressed.

18. The combination of a bowl having a rearward extension provided with a cavity and passages in its upper portion, a casing fitted in the cavity, a flushing tank secured over said casing, a cylinder passed through the bottom of the tank into the casing and means for fastening the cylinder to the casing; with a flushing valve on the outer end of said cylinder having a stem depending into the casing, a swinging dog in the casing adapted to be depressed by the stem when the valve closes, a reciprocatory catch in the casing adapted to engage the dog, a reciprocating rod pivotally connected to said catch, a swinging lever engaging said rod, a spring for moving said lever in one direction, a hinged seat and devices on said seat for moving the lever in the opposite direction when the seat is depressed.

In testimony that I claim the foregoing as my own, I affix my signature in presence of two witnesses.

WILLIAM H. LUDEWIG.
